UNITED STATES PATENT OFFICE.

ISIDOR KITSEE, OF PHILADELPHIA, PENNSYLVANIA.

PRINTING TELEGRAPHY.

No. 865,108.

Specification of Letters Patent.

Patented Sept. 3, 1907.

Application filed June 29, 1907. Serial No. 381,430.

To all whom it may concern:

Be it known that I, ISIDOR KITSEE, a citizen of the United States, residing at Philadelphia, in the county of Philadelphia and State of Pennsylvania, have invented certain new and useful Improvements in Printing Telegraphy, of which the following is a specification.

My invention relates to an improvement in printing telegraphy. Its object is, to facilitate the placing of 10 the blanks in the typewriting mechanism.

In most cases, where the printing of telegraphic messages is accomplished with the aid of devices, such as typewriters, the blanks are placed in position by manual labor and it is one of the aims of my invention to 15 substitute therefor automatic means.

It is understood that this device has more special reference to those systems of printing telegraphy, whereby through the different grouping of signals, different electro-magnets are actuated, actuating in their turn the 20 typewriting bars. In such system, it is a comparatively easy matter to arrange an additional grouping, whereby an additional or auxiliary electro-magnet is actuated.

Referring now to the drawing, in which similar letters 25 designate similar parts, Figure 1 is a partially perspective and partially diagrammatic view illustrating the roller of a typewriter, my attachment thereto, and necessary devices in conjunction therewith. Fig. 2 is a plan view of a series of blanks provided with my improvement.

1 is the roller of the typewriter or similar machine; 2, 3, 4, 5, 6 and 7 are the means to rotate the shaft. These means are here shown as the ratchet wheel 2 mounted on the shaft of the roller, the ratchet 3, the 35 armature 6 held in position by the spring 4, the electro-magnet 5 and the adjustable screw 7.

30 is an electro-magnet comprising the two electro-magnets 18 and 17, armature 9 and the contacts 10 and 27. The coil of 18 is connected with the wires 19 and 40 20, which are supposed to form part of a group of conductors adapted to actuate the typewriting mechanism. The coil of 17 is connected through wires 16 and 31 with the interposition of the battery 15 to contacting means, here shown as the two brushes 14 and 13. The armature 9 is connected with the interposition of battery 8, through wire 26, to one terminal of the coil of electro-magnet 5; and the contact 10 is connected through wire 37 with the adjustable screw 7.

The second terminal of the coil of 5 is connected electrically with the ratchet 3. The adjustable screw 7 normally contacts with the extension of ratchet 3, as this extension is drawn thereto by the spring 4. But, when, through the contacting of the armature 9 with the contact 10, a circuit is established including the 55 battery 8, then the device 5 will be energized. It will draw the armature 6 and thereby the extension of the

ratchet 3 towards its core and away from the adjustable screw 7, thereby breaking the circuit. This breaking will result in the de-magnetizing of 5 and the spring 4 will again draw the extension of 3 away from the core 60 of 5 and in contact with 7. In reality, this arrangement is a simple make and break device, whereby the ratchet actuates the wheel 2. Each make and break will move the wheel one tooth, thereby rotating the roller and causing the sheet 11 to move each one predetermined space. Normally, the armature 9 rests against the steps 27 and is, therefore, out of contact with 10.

The blanks adapted to be filled out through the typewriting mechanism are here shown as the continuous 70 sheet 11 and are illustrated as such in Fig. 2, in which 11 designates the roll of paper as an entirety comprising the separate blanks 25, separated by the perforations 23, each blank being provided with the cut out portion 12.

The operation of this device is as follows:—At the beginning, the necessary part of the first blank of the whole sheet 11 is inserted in the typewriting mechanism and positioned so, that the message can commence at the proper place. When, now, a message is completed, the operator at the transmitting station transmits a group of signals adapted to operate an electro-magnet in a manner, so as to close and electrify the circuit 19 and 20. Through the closing of this circuit, the electro-magnet 18 will become operative and will 85 draw the armature 9 towards to and in contact with the contact 10, closing the circuit including electro-magnet 5 with its make and break arrangement. The step by step movement will then be actuated in a manner well understood by persons versed in the art, and therefore the roller 1 will continuously place successive parts of the blank paper in the required position for printing. During the whole time of the drawing in of the paper, the two brushes 13 and 14 are separated from each other and the action of positioning successively, 95 successive parts of the paper will continue, till the cut-out portion 12 is reached. When this portion is at a pre-determined position, the brushes 13 and 14, formerly separated by the paper, will now come in contact with each other and will close the circuit comprising 100 13, 14, 16, 36, 15 and coil of electro-magnet 17. Through the energizing of this coil, the armature, formerly resting at 10, will move away from that contact and will move towards to and in contact with 27, thereby breaking the circuit containing electro-magnet 5 105 and the make and break device. This will effectually stop the moving of the roller and the paper will remain in the required position till a new message is to be printed thereon.

It has to be noted, that the armature 9 will remain in 110 a position brought to by the last impulse, till a new impulse drives the same in the opposite direction and it

has also to be noted that electro-magnet 18 is only momentarily energized. Briefly, therefore, it can be stated that no matter at what part of the blank the message will end, through the means adapted to be operated at the sending station, the blank will be carried through the typing mechanism for such a length of time, till the home device will stop the carrying mechanism.

Having now described my invention, what I claim 10 as new and desire to secure by Letters Patent is:—

1. In printing telegraphy, means to carry blanks, adapted to have printed thereon the message, to a predetermined position, said means comprising means adapted to be operated from the sending station to move said blanks, 15 and means adapted to be operated at the receiving station to stop said movement.
2. In combination with a typing mechanism, a continuous sheet of paper divided into a series of blanks, means to move said blanks, independent of the received message, 20 through transmitted impulses, and means to discontinue said movement through impulse locally generated.

3. In combination with a printing telegraph, means located at the receiving station and adapted to be operated in part through transmitted impulses and in part through localized impulses to carry blanks adapted to have printed thereon the message received to the required position. 25

4. In combination with a printing mechanism, a sheet of paper representing a series of blanks and means adapted to be operated through incoming impulses to move said sheet of paper, independent of the stoppage of the message proper, and stop the moving of the paper, independent of the commencing of a new message. 30

5. In combination with a printing mechanism, a step-by-step mechanism, adapted to be operated through the closing of a circuit, due to incoming impulses, in combination with local means to estop said step-by-step movement from further operation. 35

In testimony whereof I affix my signature in presence of two witnesses.
